UNITED STATES PATENT OFFICE.

ALFRED F. SEYMOUR, OF CAMPOLLO, MASSACHUSETTS.

LAST.

No. 841,725.

Specification of Letters Patent.

Patented Jan. 22, 1907.

Application filed November 15, 1905. Serial No. 287,390.

To all whom it may concern:

Be it known that I, ALFRED F. SEYMOUR, a citizen of the United States, residing at Campello, in the county of Plymouth and State of Massachusetts, have invented a new and useful Last, of which the following is a specification.

This invention relates to an improved last for making shoes.

10 The especial object of this invention is to provide a last having a metal heel-plate supported so as to prevent the last from crushing under the pressure of heel-seating machines or other devices, which now frequently crush and break the ordinary wooden lasts.

To this end this invention consists of a last having a metal heel-plate supported by the bushing which receives the supporting-pin.

In the accompanying drawings, Figure 1 is 20 a side view, partly broken away, of a last constructed according to this invention and of its supporting-pin. Fig. 2 is a fragmentary bottom view thereof. Fig. 3 is a perspective view of the metal heel-plate and its supporting-bushing, and Fig. 4 is a perspective view of the wooden block which is secured in the socket of the heel-plate.

In the lasts which are now used for making shoes sheet-metal heel-plates are employed. 30 These sheet-metal heel-plates are open at their centers to permit a central fastening-tack to be used during lasting. During the operation of heel-seating machines or other special machines a large amount of pressure is put upon the heel part of the last, and as the metal heel-plate of an ordinary last is supported only by the wood it frequently happens that the lasts are crushed or splintered. 35 Each of the ordinary lasts is provided with a metal bushing for the supporting-pin; but the heel-plate and bushing have heretofore been independent, as it was thought necessary to leave sufficient wood at the center of the heel-plate to receive the lasting-tack.

40 The especial object of my present invention is to provide a last with a heel-plate which is supported directly by its bushing, so that a metal support will be afforded for the heel-plate, allowing the same to serve as 45 an anvil without the danger of crushing or breaking the last. To accomplish this object, I preferably make the heel-plate and pin-bushing from a single piece of metal, and in order that the ordinary system of lasting

may be used I preferably fasten a small block 55 of wood in a socket near the center of the heel-plate.

Referring to the accompanying drawings and in detail, a last constructed according to this invention, as herein illustrated, comprises the usual fore part F and heel part H. These parts may be jointed, formed in a single piece, or otherwise connected in ordinary manners. In the particular construction shown the parts are hinged together by 60 a hinge secured in place by the rivets R. Mounted in the heel part of the last is a metal bushing 10, and supported and preferably formed integrally with the metal bushing 10 is a heel-plate 11. The heel-plate 11 is 65 provided near its center with a socket 12, fastened into which is a wooden block 13 for receiving the lasting-tack. The bushing 10 is held from turning by a transverse pin 15.

A pin 16 which I preferably employ for 70 supporting a last constructed according to this invention is provided with a conical end 17, and the bushing 10 is provided with a corresponding conical socket 18, this construction permitting the last to be more accurately positioned on its supporting-pin than in the ordinary construction in which the end of the pin has no engagement with the bushing.

Having thus fully described this invention, 75 what I claim as new, and desire to secure by Letters Patent of the United States, is—

As an article of manufacture, a last having a metal heel-plate and an integral projection extending therefrom, said heel-plate and projection being embedded in the heel of the last, 80 said projection having a conical socket, said plate having a recess located opposite said socket, a block of relatively soft material in the recess for receiving the lasting-tack, said 85 projection being solid between the plate and end of said socket, and a fastening-pin extending through said solid portion between the socket and recess and into the heel of the 90 last.

In testimony whereof I hereunto set my hand in the presence of two subscribing witnesses.

ALFRED F. SEYMOUR.
